COMBINED COIN HOLDER AND DISPENSER

Jack E. Browder, 45 Sacks St., Dayton, Ohio 45403

Filed Mar. 8, 1966, Ser. No. 1,355

Term of patent 14 years

(Cl. D52—4)

FIG-1

I claim:

The ornamental design for a combined coin holder and dispenser, substantially as shown.
